ELLIPSOGRAPH

William H. Christie, Altadena, Calif.

Application October 25, 1949, Serial No. 123,492

6 Claims. (Cl. 33—30)

(Granted under the act of March 3, 1883, as
amended April 30, 1928; 370 O. G. 757)

1

This invention relates to ellipsographs and more particularly to ellipsographs which will draw ellipses of large size and large eccentricity.

Most ellipsographs are very limited in their scope and will not draw ellipses of large eccentricity or large size.

It is an object of this invention to provide an ellipsograph of simple construction.

It is another object of this invention to provide an ellipsograph which will draw an ellipse of any desired eccentricity and any size within its upper limits.

It is another object of this invention to provide an ellipsograph which is very simple in operation and does not require skilled personnel to operate.

A still further object of this invention is to provide an ellipsograph which, during the scribing of the ellipse, can be removed and then replaced in position to finish the ellipse, without displacement.

Other objects and many of the attendant advantages of this invention will be readily appreciated as the same becomes better understood by reference to the following description.

The apparatus of this invention comprises generally a pair of spaced pivots on a base bar, to which are pivotally mounted a pair of actuating arms, capable of rotation in a common plane. A first cross member spans the pair of actuating arms and is pivotally connected thereto by means of adjustable slides. A second cross member similarly spans the actuating arms and is pivotally and slidably connected thereto in the same manner as the first cross member. The second cross member has a transverse member fixed perpendicular thereto and intersecting the first cross member. The transverse member and the first cross member are connected together at their intersection by means of a scribe member free to slide on either of the above members, the scribe member having a suitable pen or pencil holder attached to draw the ellipse.

In use the sliders common to the first cross member and the actuating arms are set at a distance from the pivots equal to the half minor axis of the required ellipse. The sliders common to the second cross member and the actuating arms are set at a distance equal to the half major axis of the ellipse. Then by swinging the actuating arms, the scribe member at the intersection of the transverse member and the first cross member will describe an ellipse.

The second cross member is offset outwardly at the point where the transverse arm is mounted

to permit the pivots of the two cross members to be set coaxially.

In the modifications described, only one half of an ellipse will be drawn at one time. However, the apparatus is provided with a pair of removable pins extending outwardly from the bottom of the bar and in line with the pivots. The pins can be pressed into the surface of a drafting table and the ellipsograph can then be lifted, turned 180°, and replaced on the pins to complete the second half of the ellipse which will register with the first half.

To facilitate the correct spacing of the pins without having to use the complete instrument, a spacing bar having a pair of holes therein to receive the pins may be used.

Two embodiments of the instant invention have been illustrated in the accompanying drawings, wherein:

20 Fig. 1 is a top plan view of an embodiment of the ellipsograph;

Fig. 2 is a side view of the Fig. 1 embodiment;

Fig. 3 is a top plan view of a second embodiment of the instant invention;

25 Fig. 4 is a partial section taken on line 4—4 of Fig. 3;

Fig. 5 is a plan view partially broken away, of Fig. 4;

Fig. 6 is a plan view of the spacing bar;

Fig. 7 is a side view of the spacing bar; and

Fig. 8 is a detail view of the removable pin.

Referring to Figs. 1 and 2 of the drawing, 11 designates a base bar having at its ends transverse extensions 15 terminating in a pair of spaced pivots 12, to which are mounted a pair of actuating arms 13, capable of rotation in a common plane. Slides 14 are slidably mounted, two to each of the arms 13, and can be locked in selective positions on the arms 13 by means of the set screws 16. A cross member 17 spans the actuating arms 13 and is pivotally connected at 18 to a pair of the sliders 14. A second cross member 19 similarly spans the arms 13, and is pivotally connected at 21 to the second pair of sliders 14. The second cross member 19 has a transverse member 22 mounted thereon perpendicular thereto and intersecting the cross member 17.

The transverse member 22 and the cross member 17 are connected together by means of a sliding scribe member 23 free to slide on either the cross member 17 or the transverse member 22. The scribe member 23 is provided with a suitable holder 24, for a pen or pencil attached to draw the ellipse.

The cross member 19 is offset outwardly at 26 to provide clearance for the scribe member 23 when the pivoted actuating arms are at the limits of their swing and when ellipses of small eccentricities are to be drawn.

Operation

In operation, the pivot points 21 of the cross member 19 are set at a distance from the pivots 12 equal to half the major axis of the desired ellipse by sliding the sliders 14 inwardly or outwardly (toward or away from pivots 12) along the actuating arms 13. The sliders are then locked into position by means of the set screws 16. The pivot points 18 of the cross arm 17 are set in a like manner, at a distance from the pivots 12 equal to half the minor axis of the desired ellipse and are likewise locked into position. The maximum major axis which may be used is equal to the distance between the supports of the pivots 12 of the actuating arms or twice the length of the usable length of the actuating arms. Rotating or oscillating the actuating arms 13, 180° about the pivots 12, the pen or pencil in holder 24 on the sliding scribe member 23 will describe a longitudinal half of an ellipse. It is obvious that with this embodiment of the instant invention it is necessary to draw an ellipse in two separate halves.

Second embodiment

To facilitate the completion of an entire ellipse without any displacement of the lines, the Fig. 3 embodiment is provided. This embodiment is generally similar to that of Fig. 1. However, the bar 11 has been replaced by a pair of pivot plates 11a, having a base portion 27, a leg portion 28, and a top portion 29. The actuating arms 13a are pivoted to the top portion 29 by means of the pivots 12a. The base portion 27 has therein a counterbored hole 31, in line with the pivot 12a, adapted to receive a removable pin 32 having a point 33 extending downwardly from the base portion 27.

In operation, the instant embodiment is placed into position on a drafting table and secured from lateral movement by pressing the points 33 of the pins 32 into the surface of the table. The procedure described for the operation of the first embodiment is then followed and the first half of the ellipse is drawn. The apparatus is then lifted bodily from the table, leaving the pins 32 in place on the table. The apparatus is then turned 180° into position to draw the second half of the ellipse, replaced on the pins 32, and the second half of the ellipse is completed. Since the pins 32 and the pivots 12a are on the longitudinal axis of the ellipse, and since this position has been maintained for both halves of the ellipse, there will be no displacement between the two halves and they will register perfectly.

To further simplify the operation of the above embodiment and to obviate the necessity for using the free swinging ellipsograph for positioning the removable pins 32 on the drawing table, a guide bar 34 (Fig. 6 and 7) is provided, having a pair of spaced holes 36 to receive the pins 32. The holes 36 are spaced equal to the spacing between the pairs of pivot points 18 and 21 on the cross members 17 and 19 respectively. The guide bar 34, carrying the pins 32 in the holes 36 therein, is placed over the longitudinal axis of the desired ellipse and the pins pushed into the drawing table. The bar 34 is then removed. The ellipsograph, when subsequently placed over the

pins 32, is then in position to draw the ellipse.

Obviously many modifications and variations of the present invention are possible in the light of the above teachings. It is therefore to be understood that within the scope of the appended claims the invention may be practiced otherwise than as specifically described.

The invention described herein may be manufactured and used by or for the Government of the United States of America for governmental purposes without the payment of any royalties thereon or therefor.

What is claimed is:

1. An ellipsograph comprising a pair of spaced pivots, said pivots having a pair of spaced removable pins extending from the bottom surface thereof whereby by pressing said pins into the surface of a drafting table said ellipsograph may be removed and subsequently replaced in its previous or reversed position without misalignment, a pair of actuating arms pivotably mounted on said pivots for rotation in a common plane, a pair of sliders slidably mounted on each of said actuating arms and having locking means for selectively locking said sliders to said actuating arms at selective distances from the point of pivot, a first cross member spanning said arms and pivoted at each end to one of said pair of sliders on each of said arms, a second cross member spanning said arms and pivoted to the other one of said pair of sliders on each of said arms, and having a transverse member intersecting said first cross member, said second cross member being offset outwardly at its juncture with said transverse member, and a scribe member mounted slidably on said transverse member and said first cross member at their intersection.
2. An ellipsograph comprising a pair of spaced pivots, said pivots having a pair of spaced removable pins extending from the bottom surface thereof whereby by pressing said pins into the surface of a drafting table said ellipsograph may be removed and subsequently replaced in its previous or reversed position without misalignment, a pair of actuating arms pivotably mounted on said pivots for rotation in a common plane, a pair of sliders slidably mounted on each of said actuating arms having locking means for selectively locking said sliders to said actuating arms at selective distances from the point of pivot, a first cross member spanning said arms and pivoted at each end to one of said pair of sliders on each of said arms, a second cross member spanning said arms and pivoted to the other one of said pair of sliders on each of said arms, and having a transverse member intersecting said first cross member, and a scribe member mounted slidably on said transverse member and said first cross member at their intersection.
3. An ellipsograph comprising a pair of spaced pivots, a pair of actuating arms pivotably mounted on said pivots for rotation in a common plane, a pair of sliders slidably mounted on each of said actuating arms having locking means for selectively locking said sliders to said actuating arms at selective distances from the point of pivot, a first cross member spanning said arms and pivoted at each end to one of said pair of sliders on each of said arms, a second cross member spanning said arms and pivoted to the other one of said pair of sliders on each of said arms, and having a transverse member intersecting said first cross member, and a scribe member mounted slidably on said transverse member and said first cross member at their intersection.

4. An ellipsograph comprising a pair of spaced pivots, a pair of actuating arms pivotably mounted on said pivots for rotation in a common plane, a pair of sliders slidably mounted on each of said actuating arms having locking means for selectively locking said sliders to said actuating arms at selective distances from the point of pivot, a first cross member spanning said arms and pivoted at each end to one of said pair of sliders on each of said arms, a second cross member spanning said arms and pivoted to the other one of said pair of sliders on each of said arms, and having a transverse member intersecting said first cross member, and a scribe member mounted slidably on said transverse member and said first cross member at their intersection.
5. An ellipsograph comprising a pair of spaced pivots, a pair of actuating arms pivotably mounted on said pivots for rotation in a common plane, a pair of sliders slidably mounted on each of said actuating arms having locking means for selectively locking said sliders to said actuating arms at selective distances from the point of pivot, a first cross member spanning said arms and pivoted at each end to one of said pair of sliders on each of said arms, a second cross member spanning said arms and pivoted to the other one of said pair of sliders on each of said arms, and having a transverse member intersecting said first cross member, and a scribe member mounted slidably on said transverse member and said first cross member at their intersection.

member and said first cross member at their intersection.

4. An ellipsograph comprising a pair of spaced pivots, a pair of actuating arms pivotably mounted on said pivots for rotation in a common plane, a first cross member spanning said actuating arms and pivoted thereto, a second cross member spanning said actuating arms and pivoted thereto, and having a transverse member intersecting said first cross member, and a scribe member mounted slidably on said transverse member and said first cross member at their intersection.

5. An ellipsograph comprising a pair of spaced actuating arms pivotably mounted for rotation in a common plane, a first cross member spanning said actuating arms and pivoted thereto, a second cross member spanning said actuating arms and pivoted thereto, and having a transverse member intersecting said first cross member, and a scribe member mounted slidably on said transverse member and said first cross member at their intersection.

6. An ellipsograph comprising a pair of pivot members fixedly spaced from each other, a pair of removable pins extending from the bottom surfaces of the pivot members whereby by pressing said pins into the surface of a drafting table said ellipsograph may be removed and subsequently replaced in its previous or reversed position without misalignment, a pair of parallel actuating arms pivotally mounted on said pivot

members for rotation in a common plane, a pair of sliders slidably mounted on each of said actuating arms, means for selectively locking said sliders to said actuating arms at selective distances from the point of pivot, a first cross member spanning said arms and pivoted at each end to one of said pair of sliders on each of said arms, a second cross member spanning said arms and pivoted to the other one of said pair of sliders on each of said arms, a transverse member fixed to said second cross member extending inwardly therefrom and intersecting said first cross member, said second cross member being offset outwardly at its juncture with said transverse member, and a scribe member mounted slidably on said transverse member and said first cross member at their intersection.
